US0D1091259S

(12) **United States Design Patent** (10) **Patent No.:** **US D1,091,259 S**
(45) **Date of Patent:** **** Sep. 2, 2025**

(54) **CONTAINER**

(71) Applicant: **Igloo Products Corp.**, Katy, TX (US)

(72) Inventors: **Matthew Nickel**, San Clemente, CA (US); **Adam Edward Rode**, Tacoma, WA (US); **Samantha M. Cavanaugh**, Houston, TX (US)

(73) Assignee: **Igloo Products Corp.**, Katy, TX (US)

(**) Term: **15 Years**

(21) Appl. No.: **29/869,843**

(22) Filed: **Jan. 10, 2023**

(51) **LOC (15) Cl.** **07-10**

(52) **U.S. Cl.**

USPC **D7/607**; D3/216; D3/217; D7/605

(58) **Field of Classification Search**

CLAIM

The ornamental design for a container as shown and described.

DESCRIPTION

FIG. 1 is a front perspective view of a container showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The zig zag broken lines in the figures indicate unclaimed stitching of the container that forms no part of the claimed design. The evenly spaced broken lines in the figures indicate unclaimed portions that form no part of the claimed design.

1 Claim, 8 Drawing Sheets
